R. GOODWIN

LUMINOUS SIGN

Filed March 22, 1924

Inventor

Roy Goodwin

Williams Bradbury & W. Cobb

Attorneys.

UNITED STATES PATENT OFFICE.

ROY GOODWIN, OF WILMETTE, ILLINOIS.

LUMINOUS SIGN.

Application filed March 22, 1924. Serial No. 700,994.

To all whom it may concern:

Be it known that I, ROY GOODWIN, a citizen of the United States, and resident of Wilmette, in the county of Cook and State 5 of Illinois, have invented a certain new and useful Improvement in Luminous Signs, of which the following is a full, clear, concise, and exact description, reference being had to the accompanying drawing, forming a 10 part of this specification.

My invention concerns luminous signs employing luminous paint such as the so-called radium paint, and more especially signs for displaying street numbers on 15 houses. The features of my invention include the placing of the luminous paint on an element which may be readily removed for renewing the paint, the use of unit characters which are assembled to form the 20 desired number or words, and an improved frame construction for the sign.

These and further objects and features of my invention are best set forth in the 25 following description of a particular embodiment of my invention, and in the accompanying drawings, wherein

Figure 1 is a perspective view of my device secured to a supporting surface such as 30 a door;

Figure 2 is a vertical transverse section taken on the line 2—2 of Figure 1;

Figure 3 is a plan section taken on the line 3—3 of Figure 2;

Figure 4 is a perspective of one of the 35 character units;

Figure 5 is a perspective view of the bracket member of the frame; and

Figure 6 is a detail transverse section of 40 the plate provided with a coat of luminous paint.

In the embodiment of my invention here shown, the essential parts of the sign are mounted in a frame 10 which comprises a forward wall 11 provided with a fenestration 12 leaving a peripheral margin, upper and lower walls 12, and an end wall 13, the last three walls preferably being formed by flanges bent backwardly from the forward wall. The flanges constituting the upper and lower walls 12 are turned inwardly as at 13 at their rearward edges. A channel shaped guide member 14 is soldered or otherwise secured to the under side of the upper wall 12. A similar channel shaped member 14 is provided on the up-

per side of the bottom wall 12. The channel members 14 co-operate with the inturned edges 13 and the marginal portions of the forward wall 11 to form three parallel slots in the frame. It will be noted that in forming the fenestration 12, a tongue 15 is bent inwardly from a lateral margin of the fenestration, the tongue 15 forming a closure for one end of the three slots.

In the forward slot, that is the slot between the forward wall 11 and the channel shaped members 14, is inserted a rectangular sheet of glass 16 constituting a window for the fenestration 12. In the intermediate slot, that is the slot formed between the flanges of the channel shaped members 14, are inserted a plurality of character units, such as shown in Figure 4, assembled in a row to form the desired number or words, such for example as the street number 7438 shown in Figure 1. In order to hold the characters 17 in position and to properly space them, each character is provided with an upper and a lower shoe 18. The characters 17 are preferably stamped from sheet metal, in which case the shoes 18 are an integral part of the stampings and are provided with horizontal flanges 19 of substantially the width of the intermediate slots, so that the characters are prevented from tilting forwardly and are held in a plane adjacent the rearward side of the intermediate slot. The shoes 18 of the several characters are preferably of the same length, whereby the characters may be made as standard units. In this way the dealer who sells the device may keep in stock a number of assorted characters all of the same size, and insert characters in the intermediate slot of the frame to form the number desired by the particular purchaser.

In the rearward slot, that is the slot formed between the channel shaped members 14 and the rearward inturned portions 13 of the top and bottom walls, is inserted a rectangular plate 20 of sheet metal, the forward face of which is provided with a layer of luminous paint 21, such as the radium paint now in commercial use.

While at one end of the frame the three slots are closed by the tongue 15, it will be noticed from Figure 3 that the frame carries no such closure for the opposite ends of the slots. This permits the insertion of the glass 16, the several characters 17, and the

plate 20, after the frame has been made and all of the soldering or bending operations completed. Thus, the dealer in selling the devices needs to perform no operation on the 5 frame in order to insert the desired characters into the intermediate slot.

For securing the frame 10 to a wall, door or other supporting surface, I provide a bracket 23 comprising a back plate and tapering upper and lower flanges 24, which terminate at one end of the bracket in a box-like pocket 25 consisting of an end wall 26 and a forward wall 27. Adjacent the pocket 25, the back plate of the bracket is 10 provided with a pair of holes 28 for the insertion of wood screws 29 which hold the bracket to the supporting surface. The frame 10 is placed with its rearward face adjacent the back plate of the bracket 23, 15 the upper and lower flanges 24 of the bracket being spaced apart sufficiently to fit snugly over the upper and lower walls 12 of the frame. The frame is inserted in the bracket 23 with an endwise movement, so that the 20 right end of the frame enters the pocket 25, the end wall 26 of the pocket then serving as a closure for the open ends of the three slots in the frame. For holding the frame 10 in the bracket 23, I provide a wood screw 25 30 which passes through an aperture in the left hand lateral margin of the forward wall 11 and also passes through a hole 31 at the left hand end of the bracket 23. The single wood screw 30 thus holds the frame 35 10 securely in the bracket 23 against outward or longitudinal movement.

The luminous paint 21 with which the plate 20 is provided is preferably white or of other light color, and the characters 17 40 are preferably painted black or other dark color, so that when the device is viewed in the daylight, the observer looks through the glass window 16 and sees the dark characters 17 contrasted against the light background afforded by the paint 21. As is 45 well known, the luminous paint after being exposed to the light during the daytime, will continue during the night to emanate light. Thus, when viewing the device in 50 the dark, the observer will look through the glass window 16 and see the opaque characters 17 silhouetted against the luminous background afforded by the paint 21. I prefer that the characters 17 be held in the 55 frame 12 as closely as possible to the plate 20, in order that in the daytime no confusing shadows will be cast by the characters.

It has been found that luminous paint 60 after a time loses its effectiveness in holding light rays, and for this and other reasons it is desirable from time to time to repaint the plate 20 or to substitute a new plate therefor. In order to accomplish this, the single screw 30 is removed, permitting the frame 65 to be withdrawn from the bracket 23.

When the frame is thus removed, the end wall 26 of the bracket obviously no longer functions as a closure for the open ends of the several slots, so that the plate 20 may easily be withdrawn from the rearward slot 70 and repainted. The plate is then reinserted in its slot, the frame 10 inserted in the bracket 23, and the wood screw 30 replaced. Should it be desired to change the characters 17, the frame may be removed in the 75 same manner and the characters withdrawn from the intermediate slot and the desired characters substituted. Similarly, the glass window 16 may be replaced if broken.

While I have shown but this particular embodiment of my invention, it is to be understood that changes may be made therein without departing from the spirit or scope of my invention.

Having thus described my invention, I claim:

1. A luminous street number sign comprising a frame having top and bottom walls, front and rear flanges projecting inwardly from the front and rear edges of 80 said top and bottom walls, a member of channel section extending along one of said walls, the flanges of said channel member being spaced from said front and rear flanges, thereby forming three slots distributed transversely of the frame, a glass pane in the front slot, indicating characters in the central slot, and a luminous plate in the rear slot.

2. A street number sign comprising a 100 frame open at one end indicating characters supported by said frame insertable through said open end, a luminous background supported by said frame, a mounting bracket for attachment to a wall or the like, and 105 cooperating horizontal guide surfaces on said bracket and on said frame adapting said frame to horizontal sliding motion into and out of said bracket, said bracket closing the open end of said frame.

3. A luminous house number sign comprising a frame having top and bottom channels, a plurality of separate interchangeable characters adapted to be received in 115 said channels, and shoes at top and bottom of each character of semi-circular cross section for resilient gripping in said channels.

4. A street number sign comprising a frame, having a top wall, a bottom wall and one end wall, marginal flanges projecting inwardly from said walls, a second pair of flanges between said marginal flanges forming three slots transversely of said frame, a glass pane in the front slot, indicating characters in the central slot, and a luminous plate in the rear slot, said slots being open at the open end of said frame, a mounting bracket for securing to a point of attachment, said bracket having top and bottom guide flanges, and an end pocket, said 130

frame being inserted between said top and bottom guide flanges and having its open end slid into said end pocket.

5. A luminous street number sign comprising a frame, slot means in said frame, a plurality of cut-out character units assembled in said slot means, a plate in said slot means, said plate being disposed behind said units and being provided with luminous paint for forming a luminous background for said units, said slot means being open at one end for permitting insertion of said units and insertion and renewal of said plate, a bracket for securement to a wall, and means on said bracket for removably holding said frame, said bracket comprising a closure for said open end of said slot means.
6. A luminous street number sign comprising a plurality of cut-out characters, a frame therefor, guide means on said frame for slidably supporting said characters, one end of said guide means being open for permitting the insertion of said characters, a bracket member for holding said frame comprising a closure for said open end, said bracket member having guide surfaces between which said frame is slidably inserted, and a background of luminous paint behind said characters.
7. A luminous street number sign comprising a frame, a plurality of characters carried thereby, a plate provided with luminous paint forming a background for said characters, guide means on said frame for slidably supporting said plate, one end of said guide means being open for permitting the insertion and withdrawal of said plate, and a bracket member for holding said frame comprising a closure for said open end said frame being adapted to be slid endwise into supported relation in said brackets and means for removably securing said bracket member to a supporting surface.
8. A luminous street number sign comprising a frame, forward, intermediate and rear slots in said frame, a sheet of transparent material constituting a window disposed in said forward slot, a row of cut-out characters of opaque material disposed in said intermediate slot, and a plate provided with a layer of luminous paint disposed in said rear slot, and means for securing said frame to a supporting surface.

In witness whereof, I hereunto subscribe my name this 17th day of March, 1924.

ROY GOODWIN.
